PAN GUIDEWAY FOR ROTARY MINING HEAD

Charles E. Compton, Clarksburg, W. Va.

Application September 22, 1952, Serial No. 310,768

13 Claims. (Cl. 262—9)

This invention relates to mining machines comprising a carriage, a supporting structure along which the carriage is adapted to be advanced, a mining head operatively coupled to the carriage, means for rotating the head and means for advancing the carriage along the supporting structure to propel the head into a body of material to be mined while the head rotates. The invention contemplates the provision of a pan underlying the head at the end of the machine toward which the carriage advances and forming a guideway.

In machines of the type in question the coupling between the mining head and the carriage is not perfectly rigid. Consequently, as the carriage advances at the beginning of a mining operation before the mining head has entered the body of material to be mined there may be a slight sagging of the mining head resulting in starting a hole in the material to be mined whose axis is not exactly parallel to the direction of movement of the carriage. I provide for guiding the head as it is propelled to and into the body of material to be mined by utilizing a pilot pan underlying the head. The pilot pan may be connected with the supporting structure of the machine and may project forwardly thereof. It guides the mining head sufficiently to obviate sagging prior to the time when the head enters the body of material to be mined and thereby in effect forms its own guide.

The pan forms a guideway extending in the direction of advance of the carriage underlying the head. The guideway is a guideway for the head before the head enters the body of material to be mined as above explained. It may also serve as a guideway for material expelled from the body of material to be mined by operation of the mining head. I preferably mount the pan advanceably in the supporting structure so that it may be advanced to span the gap between the supporting structure and the body of material to be mined to serve as a support for material passing from the body of material toward the machine. I preferably provide means for advancing the pan in the direction of advance of the carriage to a position in which the forward edge of the pan is in immediate proximity to the body of material to be mined.

The supporting structure preferably carries guide means and the pan is preferably disposed in guided relationship to the guide means for movement in the direction of advance of the carriage to a location in which the forward edge of the pan is in the desired operative position. The pan may be made of steel plate which may be of heavy enough gauge to be substantially rigid, or it may be made of lighter material appropriately reinforced. The pan in any event is strong and rigid enough to perform the above ascribed functions.

The mining machine may be provided with a conveyor for conveying away the material expelled from the body of material to be mined by the rotating and advancing mining head. The pan forms a guideway extending in the direction of advance of the carriage underlying the head and projecting forwardly of the supporting struc-

2

ture receiving the expelled material and supporting it in its movement to the conveyor. Rotation of the mining head moves the expelled material rearwardly in the guideway provided by the pan.

5 The pan may have an opening through the bottom thereof at the rearward portion thereof to permit material moving along the pan to drop through the opening onto the conveyor. The opening has its primary utility when the pan is in retracted position, i. e., not advanced toward the body of material to be mined. When the pan is in fully retracted position its rear end may be above the conveyor and to prevent the pan from delivering its material past the conveyor the opening through its bottom is provided. When the pan is projected toward the body of material to be mined the material propelled away from the body of material to be mined passes along the pan and thence along a portion of the supporting structure to the conveyor.

20 Means are preferably provided which are connected with the supporting structure and with the pan for advancing the pan relatively to the supporting structure in the direction of advance of the carriage. In the form of structure shown in the drawings such means comprises a pair of hydraulic jacks connected with the supporting structure and with the pan at opposite sides thereof.

Other details, objects and advantages of the invention will become apparent as the following description of a present preferred embodiment thereof proceeds.

25 30 In the accompanying drawings I have shown a present preferred embodiment of the invention in which

Figure 1 is a side elevational view of a mining machine showing the machine engaged in a mining operation;

35 Figure 2 is a fragmentary plan view to enlarged scale of the forward portion of the mining machine shown in Figure 1 but, for clarity of showing, omitting the mining head and the transverse conveyor;

40 Figure 3 is a front elevational view of the structure shown in Figure 2, also showing a portion of the carriage for advancing the mining head and indicating the position of the mining head in chain lines; and

45 Figure 4 is a perspective view of the structure shown in Figure 2 but with a portion cut away.

Referring now more particularly to the drawings, the mining machine may be of the general type shown in my Patent No. 2,616,677 and my copending applications Serial Nos. 202,898, filed December 27, 1950, and 308,369, filed September 8, 1952. The supporting structure may comprise a massive elongated frame 10 having

50 side structural members 11 rigidly joined at the rear ends thereof by a bolster 12 welded or otherwise affixed to the structural members 11. At spaced intervals toward the forward end 13 of the frame 10 spanning structural members 14 in the form of plates having a generally inverted or convex downwardly profile are also joined to the respective side structural members 11 by welding or otherwise. Thus the frame 10 is generally trough-shaped with the forward end 13 thereof open. A pan 15 which is convex downwardly and concave upwardly

55 fits the profile of the plates 14 and is connected with the plates as by welding. The upper edges of the pan 15 are affixed to the side structural members 11. The various frame members such as the side structural members 11 may be tubular and I prefer to make them of well casing

60 pipe which is of optimum strength. The frame may be supported on pontoons P on which it may be moved from place to place during use.

65 70 The mining machine comprises a carriage designated generally by C and has a mining head H operatively coupled thereto at its forward end. Means comprising a motor M carried by the carriage are provided for rotat-

ing the head so that when the carriage is advanced along the supporting structure or frame the mining head can while rotating be propelled forwardly of the frame and into a coal seam or other body of material to be mined. A coal seam is designated S in Figure 1. The mining head may be of the character of the heads of my Patents Nos. 2,562,841 and 2,594,256, comprising a portion for severing material from the body of material being mined and a portion for conveying rearwardly the severed material. The length of the mining head H may be increased by inserting conveyor sections. Since the present invention does not reside in the structure of the mining head or the means for rotating it that structure and means are not shown and described in detail.

The supporting structure or frame is provided with opposed tracks 16 which open toward each other and which receive rollers 17 mounted in the carriage C on vertical shafts 18 and projecting laterally from the carriage into the tracks 16. The rollers 17 thus support the carriage for guided movement along the frame. In operation the carriage is advanced a certain distance toward the material being mined when the mining head is uncoupled from the carriage and the carriage is retracted and an additional conveyor section inserted whereafter the carriage is again advanced while the mining head is rotated. The cycle may be repeated a number of times so that a hole may be drilled into the material being mined for a distance of several hundred feet although the conveyor sections may have a length of the order of twenty or thirty feet. The material being mined is delivered out of the hole by the head H and is removed by a conveyor J. The pan 15 has a cut out portion K to accommodate the conveyor J. After the hole has been drilled to the desired depth with recovery of the material therefrom the carriage is alternately retracted to pull the mining head out of the hole and, after removal of a conveyor section, advanced, recoupled to the mining head and again retracted, the cycle being repeated until the mining head has been completely removed from the hole.

I mount in the carriage C a shaft 19 extending transversely of the direction of movement of the carriage, the shaft being journaled in fixed bearings for rotation. Fixed to the shaft 19 are two drums 20, one adjacent each side of the carriage. Each of the drums is of generally cylindrical shape but preferably has a groove 21 in its outer generally cylindrical surface, the groove 21 extending about the drum and progressing axially thereof like a screw thread. The groove 21 is shaped to fit the contour of an elongated flexible element shown as being a wire rope although other equivalent elements may be employed. Fixed to the shaft 19 is a driving sprocket 22. Mounted in the carriage is an oil motor 23 connected through a transmission 24 to a gear reducer 25 having a shaft 26 parallel to the shaft 19 and carrying a sprocket 27 coplanar with the sprocket 22. A sprocket chain 28 extends about and meshes with the sprockets 22 and 27 whereby the motor 23 rotates the shaft 19. Provision is made either in the motor or in the transmission for driving the shaft 19 in either direction as desired.

A wire rope 29 extends generally longitudinally of the frame adjacent each side of the carriage. Each end of each of the wire ropes 29 is connected to the frame adjacent an end thereof through a resilient connector 30, there being four such resilient connectors, one for each end of each of the two wire ropes. Thus when the shaft 19 is driven the respective wire ropes will be wound up on the drum in one direction and payed out from the drum in the opposite direction, thereby moving the carriage along the frame. The driving means for the carriage is claimed in my copending application Serial No. 308,369, filed September 8, 1952.

Fastened to the upper face of the pan 15 adjacent the forward end of the machine are opposed longitudinally extending guides 31 which may as shown in Figure 3 be made up of steel plates welded together and to the pan.

Each of the guides 31 has an inwardly open throat 32. Mounted at the forward end of the machine and underlying the head H is a shorter pan 33 which is upwardly open and forms a guideway extending in the direction of advance of the carriage C. The pan 33 may be made of a bent steel plate and has attached to the outer face thereof longitudinally extending flanges 34 entering the throats 32 of the respective guides 31 so that the pan 33 is guided by the guides 31 for longitudinal movement. Only sufficient clearance is provided for the flanges 34 in the guides 31 to permit of longitudinal movement of the pan 33. Thus the pan is by the guides rather accurately positioned for movement longitudinally of the machine. One of the members 35 of each guide 31 has its inner edge spaced slightly outwardly from the outer edge of the corresponding flange 34 whereby the pan 33 is maintained centered and its movement in a substantially straight line longitudinally of the machine is insured. The bottom of the pan 33 is supported and guided upon a saddle 33a mounted on the pan 15 centrally at the bottom thereof.

For moving the pan 33 longitudinally of the machine I provide two hydraulic jacks 36 each connected with the pan 33 at 37 and with the pan 15 at 38. Suitable control means are provided for the jacks so that they are operated synchronously. The hydraulic jacks operate to move the pan 33 longitudinally of the machine while being guided by the guides 31 and the saddle 33a. In Figures 2 and 4 the pan 33 is shown as being in its fully retracted position, i. e., the position in which it is withdrawn rearwardly to the fullest extent, while in Figure 1 the pan is shown advanced with its forward edge in contact with the seam S. It may be advanced to any desired position within the limits prescribed by the length of the jacks 36.

When the head H is in retracted position it lies upon the pan 33. During the initial forward movement of the head before the head enters the body of material to be mined it is guided by the pan 33. As the head H advances the pan 33 may be advanced by the jacks 36 so as to continue to guide the head until the head enters the body of material to be mined whereafter the head is guided by the bore which it makes in the body of material to be mined. The pan 33 may be advanced until its forward edge is in immediate proximity to the body of material to be mined. Normally it will be thrust forward by the jacks 36 until its forward edge engages and presses against the body of material to be mined immediately below the hole formed therein by the head H as shown in Figure 1. Thus the pan 33 forms a guideway extending in the direction of advance of the carriage which projects forwardly of the supporting structure and receives the material expelled by the head and supports it in its rearward movement, i. e., in its movement away from the body of material to be mined.

The pan 15 is cut away between the lines 39 and 40 viewing Figures 2 and 4 to provide the cut out portion or opening K and the conveyor J has a portion positioned beneath the opening thus formed. The material removed from the body of material to be mined by the head H is conveyed rearwardly by the conveying portion of the head and is guided by the pan 33 until it drops through the opening K in the pan 15 whence it is conveyed away by the conveyor J. When the pan 33 is projected forwardly the material may be guided first by the pan 33 and then by the pan 15 before it drops onto the conveyor J. To provide for large lumps of material dropping onto the conveyor J when the pan 33 is fully retracted the pan has an opening 41 through the bottom thereof at the rearward portion thereof as shown in Figures 2 and 4.

Thus the pan 33 may perform a dual function, being first a pilot pan for the head H to guide the head as it is propelled to and into the body of material to be mined and forming thereafter a guideway extending longitudinally of the machine for guiding rearwardly the material removed from the body of material to be mined by the

head H as operation of the head forces that material rearwardly. In other words, the pan 33 constitutes a guideway first for the head and then for the mined material. In its capacity as a guideway for the head it insures entry of the head into the body of material to be mined at the proper angle. In its capacity as a guideway for the mined material it obviates spillage of a considerable quantity of the mined material upon the ground outside the hole being formed by the head H in the body of material to be mined. Thus the recovery of an unprecedented proportion of the mined material is obtained without cleaning up outside the hole. Also, the depositing of mined material outside the hole which might interfere with movement of the machine along the body of material to be mined is obviated.

While I have shown and described a present preferred embodiment of the invention it is to be distinctly understood that the invention is not limited thereto but may be otherwise variously embodied within the scope of the following claims.

I claim:

1. In a mining machine comprising a carriage, a supporting structure along which the carriage is adapted to be advanced, a mining head operatively coupled to the carriage, means for rotating the head and means for advancing the carriage along the supporting structure to propel the head into a body of material to be mined while the head rotates, an upwardly open pilot pan at the end of the machine toward which the carriage advances whose central portion underlies the head in contact with the head and thereby guides the head as it is propelled to and into the body of material to be mined, the head having means which while the head rotates deliver material being mined to the pilot pan.

2. In a mining machine comprising a carriage, a supporting structure along which the carriage is adapted to be advanced, a mining head operatively coupled to the carriage, means for rotating the head and means for advancing the carriage along the supporting structure to propel the head into a body of material to be mined while the head rotates, an upwardly open pilot pan at the end of the machine toward which the carriage advances whose central portion underlies the head in contact with the head and thereby guides the head as it is propelled to and into the body of material to be mined, the pilot pan being mounted in the supporting structure, the head having means which while the head rotates deliver material being mined to the pilot pan.

3. In a mining machine comprising a carriage, a supporting structure along which the carriage is adapted to be advanced, a mining head operatively coupled to the carriage, means for rotating the head and means for advancing the carriage along the supporting structure to propel the head into a body of material to be mined while the head rotates, an upwardly open pilot pan at the end of the machine toward which the carriage advances whose central portion underlies the head in contact with the head and thereby guides the head as it is propelled to and into the body of material to be mined, the pilot pan being advanceably mounted in the supporting structure so that it may be advanced to span the gap between the supporting structure and the body of material to be mined to serve as a support for material passing from the body of material toward the machine.

4. In a mining machine comprising a carriage, a supporting structure along which the carriage is adapted to be advanced, a mining head operatively coupled to the carriage, means for rotating the head and means for advancing the carriage along the supporting structure to propel the head into a body of material to be mined while the head rotates, an upwardly open pan forming a guideway extending in the direction of advance of the carriage and whose central portion underlies the head in contact with the head and thereby guides the head as it is propelled to and into the body of material to be mined.

and means for advancing the pan in the direction of advance of the carriage to a position in which the forward edge of the pan is in immediate proximity to the body of material to be mined.

5. In a mining machine comprising a carriage, a supporting structure along which the carriage is adapted to be advanced, a mining head operatively coupled to the carriage, means for rotating the head and means for advancing the carriage along the supporting structure to propel the head into a body of material to be mined while the head rotates, guide means carried by the supporting structure and an upwardly open pan forming a guideway extending in the direction of advance of the carriage and whose central portion underlies the head in contact with the head and thereby guides the head as it is propelled to and into the body of material to be mined, the pan being in guided relationship to the guide means for movement in the direction of advance of the carriage to a position in which the forward edge of the pan is in immediate proximity to the body of material to be mined.

6. In a mining machine comprising a carriage, a supporting structure along which the carriage is adapted to be advanced, a mining head operatively coupled to the carriage, means for rotating the head, means for advancing the carriage along the supporting structure to propel the head into a body of material to be mined while the head rotates and thereby expel material from said body and a conveyor for conveying away the thus expelled material, an upwardly open pan forming a guideway extending in the direction of advance of the carriage and whose central portion underlies the head in contact with the head and thereby guides the head as it is propelled to and into the body of material to be mined, the pan projecting forwardly of the supporting structure receiving the expelled material and supporting it in its movement to the conveyor.

7. In a mining machine comprising a carriage, a supporting structure along which the carriage is adapted to be advanced, a mining head operatively coupled to the carriage, means for rotating the head, means for advancing the carriage along the supporting structure to propel the head into a body of material to be mined while the head rotates and thereby expel material from said body and a conveyor for conveying away the thus expelled material, an upwardly open pan forming a guideway extending in the direction of advance of the carriage and whose central portion underlies the head in contact with the head and thereby guides the head as it is propelled to and into the body of material to be mined, the pan projecting forwardly of the supporting structure receiving the expelled material and supporting it in its movement to the conveyor, the pan having an opening through the bottom thereof at the rearward portion thereof above a portion of the conveyor to permit material moving along the pan to drop through the opening onto the conveyor.

8. In a mining machine comprising a carriage, a supporting structure along which the carriage is adapted to be advanced, a mining head operatively coupled to the carriage, means for rotating the head, means for advancing the carriage along the supporting structure to propel the head into a body of material to be mined while the head rotates and thereby expel material from said body and a conveyor for conveying away the thus expelled material, an upwardly open pan forming a guideway extending in the direction of advance of the carriage and whose central portion underlies the head in contact with the head and thereby guides the head as it is propelled to and into the body of material to be mined, the pan projecting forwardly of the supporting structure receiving the expelled material and supporting it in its movement to the conveyor and guide means on the supporting structure supporting the pan for movement in the direction of advance of the carriage so that the pan may

be advanced to a position in which its forward edge is in immediate proximity to the body of material to be mined.

9. In a mining machine comprising a carriage, a supporting structure along which the carriage is adapted to be advanced, a mining head operatively coupled to the carriage, means for rotating the head and means for advancing the carriage along the supporting structure to propel the head into a body of material to be mined while the head rotates, an upwardly open pan forming a guideway extending in the direction of advance of the carriage at the end of the machine toward which the carriage advances and whose central portion underlies the head in contact with the head and thereby guides the head as it is propelled to and into the body of material to be mined and means connected with the supporting structure and with the pan for advancing the pan relatively to the supporting structure in the direction of advance of the carriage.

10. In a mining machine comprising a carriage, a supporting structure along which the carriage is adapted to be advanced, a mining head operatively coupled to the carriage, means for rotating the head and means for advancing the carriage along the supporting structure to propel the head into a body of material to be mined while the head rotates, guide means carried by the supporting structure, an upwardly open pan forming a guideway extending in the direction of advance of the carriage at the end of the machine toward which the carriage advances and whose central portion underlies the head in contact with the head and thereby guides the head as it is propelled to and into the body of material to be mined, the pan being in guided relationship to the guide means for movement in the direction of advance of the carriage and means connected with the supporting structure and with the pan for advancing the pan relatively to the supporting structure in the direction of advance of the carriage.

11. In a mining machine comprising a carriage, a supporting structure along which the carriage is adapted to be advanced, a mining head operatively coupled to the carriage, means for rotating the head and means for advancing the carriage along the supporting structure to propel the head into a body of material to be mined while the head rotates, guide means carried by the supporting structure, an upwardly open pan forming a guideway extending in the direction of advance of the carriage at the end of the machine toward which the carriage advances and whose central portion underlies the head in contact with the head and thereby guides the head as it is propelled to and into the body of material

to be mined, the pan being in guided relationship to the guide means for movement in the direction of advance of the carriage and a pair of hydraulic jacks connected with the supporting structure and with the pan at opposite sides thereof for advancing the pan relatively to the supporting structure in the direction of advance of the carriage.

12. In a mining machine comprising a carriage, a supporting structure along which the carriage is adapted to be advanced, a mining head operatively coupled to the carriage, means for rotating the head and means for advancing the carriage along the supporting structure to propel the head into a body of material to be mined while the head rotates, an upwardly open pan forming a guideway extending in the direction of advance of the carriage at the end of the machine toward which the carriage advances and whose central portion underlies the head in contact with the head and thereby guides the head as it is propelled to and into the body of material to be mined, a saddle mounted on the supporting structure and underlying the pan in supporting and guiding relationship thereto and means for moving the pan generally in the direction of advance of the carriage.

13. In a mining machine comprising a carriage, a supporting structure along which the carriage is adapted to be advanced, a mining head operatively coupled to the carriage, means for rotating the head and means for advancing the carriage along the supporting structure to propel the head into a body of material to be mined while the head rotates, an upwardly open pan forming a guideway extending in the direction of advance of the carriage at the end of the machine toward which the carriage advances and whose central portion underlies the head in contact with the head and thereby guides the head as it is propelled to and into the body of material to be mined, supporting and guiding means for the pan carried by the supporting structure cooperating with the pan in the region of its bottom and in the regions of its sides and means for moving the pan generally in the direction of advance of the carriage.
